UNITED STATES PATENT OFFICE.

JARROT L. ROLLINS, OF COLFAX, CALIFORNIA.

ADJUSTABLE CALENDAR.

1,186,835.

Specification of Letters Patent. Patented June 13, 1916.

Application filed April 28, 1915. Serial No. 24,432.

To all whom it may concern:

Be it known that I, JARROT L. ROLLINS, a citizen of the United States, residing at Colfax, in the county of Placer and State 5 of California, have invented new and useful Improvements in Adjustable Calendars, of which the following is a specification.

This invention relates to a device which provides a convenient calendar showing the 10 days of the week and the months, and means to so adjust the device that the days of the week shall correspond with the days of the month on which they occur.

It consists in a novel combination of parts 15 with their adjustable features, and in details of construction, which will be more fully described by reference to the accompanying drawings in which—

Figure 1 is a plan view. Fig. 2 is a transverse section at 2—2, Fig. 1.

The body or main portion of my device consists of a rectangular strip of any suitable length. It is here illustrated as representing a rule A, which may have divisions of length marked upon one edge either 20 in inches and subdivisions, 2, or a metric system, or both upon opposite sides. The device may be made of a substance suitable for the purpose. Longitudinally from end 25 to end upon one side, a channel 3 is made having projecting edges, so as to form a substantially dovetailed channel and guide, in which a slidable strip of material 4 is fitted and adjustable in either direction along the 30 channel.

Along the margin of the channel, the 35 days of the week are indicated as at 5, and repeated as often as required and the slidable strip is in like manner marked with the 40 days of the month as at 6. The number of days in a month are marked, as at 8, so that the first day of a month may coincide with

the day of the week in the particular month, to be referred to. This coincidence will be effected by slipping the sliding portion one way or other along the guide channel to the desired point. It is then retained in place by a locking device 7, which may have one end pivoted to the main part of the device and the downturned opposite end is adapted to 45 engage holes in the slide 4, so as to retain it in the position to which it may have been moved. Advertising and other matter may be printed upon the vacant spaces on the device.

This construction enables me to conveniently assemble in a single structure a calendar and a measuring scale, which may be conveniently carried in the pocket.

Having thus described my invention, 60 what I claim and desire to secure by Letters Patent is—

In an adjustable calendar of the rule type having a slidably mounted strip provided with the days of the month adapted to register with the days of the week provided on the rule, said slidable strip being formed with a series of holes, a locking device comprising a length of wire pivoted at one end to the rule and having its opposite end free 65 and downturned to engage selectively in the holes of the strip, the intermediate portion of the wire length being arched to afford a grip for manipulating the locking device and the pivoted end extending through the rule and 70 headed to prevent said end from pulling out.

In testimony whereof I have hereunto set my hand in the presence of two subscribing witnesses.

JARROT L. ROLLINS.
